(57) **CLAIM**

The ornamental design for a display screen with animated graphical user interface, as shown and described.

DESCRIPTION

FIG. 1 is a front elevational view of a display screen with animated graphical user interface showing our new design; FIG. 2 is a front elevational view of a second image thereof; FIG. 3 is a front elevational view of a third image thereof; FIG. 4 is a front elevational view of a fourth image thereof; FIG. 5 is a front elevational view of a fifth image thereof; FIG. 6 is a front elevational view of a sixth image thereof; FIG. 7 is a front elevational view of a seventh image thereof; FIG. 8 is a front elevational view of an eighth image thereof; FIG. 9 is a front elevational view of a ninth image thereof; and,

FIG. 10 is a front elevational view of a tenth image thereof. The even broken line at the periphery of the figures illustrates the display screen, and the remaining even broken lines illustrate portions of the animated graphical user interface. None of the broken lines form part of the claimed design.

The appearance of the transitional image sequentially transitions between the images shown in FIGS. 1-10. The process or period in which one image transitions to another image forms no part of the claimed design.

1 Claim, 10 Drawing Sheets
